UNITED STATES PATENT OFFICE.

GILBERT S. GRAVES, OF BUFFALO, NEW YORK, AND JACOB HEEDE, OF PEORIA, ILLINOIS.

FEED-REGULATOR FOR GRINDING-MILLS.

SPECIFICATION forming part of Letters Patent No. 252,211, dated January 10, 1882.

Application filed November 4, 1881. (No model.)

To all whom it may concern:

Be it known that we, GILBERT S. GRAVES, of the city of Buffalo, in the county of Erie and State of New York, and JACOB HEEDE, of Peoria, in the State of Illinois, have invented new and useful Improvements in Feed-Regulators for Grinding-Mills, of which the following is a specification.

This invention relates more particularly to horizontal-disk grinding-mills which are employed for grinding grain, together with a stream of water in manufacturing starch. The grain which is fed into the eye of the running-stone in this manufacture is more or less soft and adhesive, by reason of a previous soaking, and is very apt to clog up the eye of the running-stone, and thereby interfere with a steady and uniform feed.

The object of our invention is to avoid this difficulty; and it consists of a distributing mechanism arranged in the eye of the running-stone, whereby the material is fed between the grinding-surfaces uniformly and without interruption, as hereinafter fully set forth.

In the accompanying drawings, Figure 1 represents a vertical section of a pair of millstones provided with our improvements. Fig. 2 is a sectional view of the distributing mechanism and the adjacent parts of the millstones, on an enlarged scale, at right angles to Fig. 1. Figs. 3 and 4 are elevations at right angles to each other, and Fig. 5 a top plan view of the distributing-spouts; and Fig. 6 is a perspective view of the guard-ring applied to the bed-stone.

Like letters of reference refer to like parts in the several figures.

A represents the stationary frame of the mill; B, the bed-stone; C, the bushing thereof; D, the mill-spindle; E, the bail; F, the running-stone; F', the eye thereof, and G the curb, all of ordinary and well-known construction.

H represents the distributing-spout, arranged in the eye F' of the running-stone, and secured to the bail E, so as to revolve therewith. As shown in the drawings, the distributing-spout is provided with two legs or discharge nozzles, H', arranged diametrically opposite each other, and extending downward to within a short distance of the top of the bed-stone. The lower ends of the nozzles H' are cut off obliquely, their forward edge being the deepest, and the bottom of the nozzle rising rearwardly, as indicated by the arrows in Fig. 4.

I represents the adjustable feed-tube, of ordinary construction, depending into the upper portion of the distributing-spout H, and K is the revolving saucer or concave plate, arranged on the bail underneath the feed-tube, for distributing and delivering the material from the feed-tube I into the feed-spout H. i is the water-pipe, through which a stream of water is conducted to the saucer K. The saucer K is provided on its under side with a screw, k, which penetrates the saddle or bottom of the distributing-spout H at the junction of the nozzles H', and which taps into the bail E, whereby both the saucer and the distributing-spout are firmly secured to the bail.

L represents the guard-ring arranged on the upper side of the bed-stone B, within the lower enlarged portion of the eye of the runner, and outside of the lower ends of the nozzles H'. The ring L is secured to the bushing C of the bed-stone B by angle-bars l, which overlap the bushing, and are secured thereto by screws or other suitable means.

m represents perforations formed in the lower portion of the ring L for the purpose of permitting the water to escape therefrom.

The grain is fed into the feed-tube I, and a stream of water through the pipe i in any well-known and suitable manner, and passes into the revolving saucer K, by which the material is delivered into the distributing-spout H, from which it escapes through the nozzles H' into the annular space within the ring L, wherein it accumulates until it is removed by the revolving nozzles. The depressed front edges of the nozzles force the material outward over the upper edge of the ring L and against the lower face of the running-stone F, and the latter then seizes the material and forces it outward between the grinding-faces in a well-known manner. As the depressed front edges of the nozzles H' remove the material from within the ring L they make room for the material contained in the nozzles, and the material is in consequence discharged from the nozzles in a uniform stream. The perforations near the bottom of the ring L permit the free escape of the

water from the space within the ring, and prevent the water from accumulating therein and interfering with the proper discharge of the material from the nozzles. The ring L also 5 serves to intercept heavy metallic substances— such as nails, screws, and metallic fragments— which may be contained in the grain, as these substances tend by gravity to work to the bottom of the layer of material within the ring and 10 accumulate within the same, and are moved inward toward the spindle by the oblong shape of the nozzles. These metallic particles are readily removed from time to time, and in this manner prevented from injuring the grinding- 15 faces of the stones.

It is obvious that only one nozzle H' may be employed, if desired; but we prefer the arrangement of two nozzles, as shown in the drawings.

20 We claim as our invention—

1. The combination, with the running-stone F, provided with a revolving distributing-spout H, having one or more discharge-nozzles, H', arranged in the eye of the runner, of the bed-stone B, provided with a guard-ring, L, substantially as set forth.

2. The combination, with the running-stone F, provided with a revolving distributing-spout, H, having one or more discharge-nozzles, H', arranged in the eye of the runner, of the bed- 30 stone B, provided with a guard-ring, L, having perforations m, substantially as set forth.
